UNITED STATES PATENT OFFICE.

GEORGE L. CRAGG, OF CHICAGO, ILLINOIS, ASSIGNOR TO HARRY A. DOUGLAS, OF BRONSON, MICHIGAN.

ELECTRIC SWITCH.

Application filed January 24, 1927. Serial No. 163,145.

My invention relates to electric current conducting winding elements and to circuit controlling switches in electrical association therewith.

5 The invention finds particular utility in connection with spark producing circuit systems employed for producing sparks in cylinders of internal combustion engines that are employed in the power plants of automobiles or other automotive vehicles. The invention has for its general object the provision of an improved assembly of the winding elements, the cores of such elements, and the associated switches whereby the switches 10 and the circuit terminals thereat are guarded from unwarranted access and the combined structures are simplified and occupy less space than hitherto.

In carrying out my invention the winding 20 element is provided with a magnetizable core, the switch being preferably abreast of the core on one side thereof and the switch actuating means, which is preferably a locking mechanism, being upon the other side 25 of the core and preferably also abreast thereof and operatively connected with the switch by a lever which extends across the core. The winding element is desirably continued into the zone occupied by the switch and the 30 locking mechanism. The spacing that contains the switch and locking mechanism is closed by an end plate or wall which is applied to the adjacent end of the winding element to constitute with the winding element a casing which effectively protects the 35 switch and locking mechanism. In the preferred embodiment of the invention the locking mechanism is key operated, the key constituting an operating handle which is engageable upon the exterior of the casing.

40 The invention will be more fully explained in connection with the accompanying drawings in which Fig. 1 is a longitudinal sectional view of one embodiment thereof; Fig. 45 2 is a sectional view of a part of the structure on line 2-2 of Fig. 1; Fig. 3 is a sectional view on line 3-3 of Fig. 1; Fig. 4 is a sectional view on line 4-4 of Fig. 1, on a smaller scale; Fig. 5 is a front view illustrating a portion of the dash board or other mounting and the structure of my invention in assembly therewith; Fig. 6 is a perspective view with portions broken away of parts of the structure, one of which is separated 50 from the remainder; Fig. 7 is a perspective

view of a locking mechanism and a switch lever arm controlled thereby; and Fig. 8 is a diagram of one ignition circuit that may be employed, the invention not being limited, however, to any particular ignition circuit. 60

The hollow current conducting element illustrated is inclusive of a generally cylindrical and tubular primary winding 1 and a generally cylindrical and tubular secondary winding 2 of a so-called induction coil. The 65 primary winding has one terminal grounded through a battery 3 and has another terminal connected by a metallic binding screw 4 with a metallic contact sleeve 5, which is carried by and passes through a normally 70 stationary insulating disc section or block 6 whose curved side is coaxial with the winding element 1, 2 and which disc is surrounded by the secondary thereof, in this instance. Another metallic contact sleeve 7 is carried 75 by said disc section or block 6, this contact sleeve receiving a conductor clamping metallic screw 8. The screws 4 and 8 are upon the rear face of the disc section or block 6 which is made hollow to receive them and the wire 80 ends connected therewith, the contact sleeves 5 and 7 passing through the disc section or block to be engageable at its front face, and by the adjacent contacts that are formed upon the inner ends of the metallic spring 85 barrels 9 and 10 which are mounted upon and electrically connected by the floating metallic bridging bar 11. Springs 14 in said 90 spring barrels press the plungers 15, 16 forwardly against the contact actuating bar 17 that is formed of insulation, said spring barrels being slidably received in recesses formed in bar 17, said plungers engaging the bottoms of said recesses. As will hereinafter appear, the contact actuating bar 17 is adapt- 95 ed to be turned by a key 18 that acts as a separable handle to bring the bridging bar 11 and the contacts thereon into and out of engagement with the contacts 5 and 7. The screw 8 connects the conductor 19 with the 100 contact 7, this conductor extending to the circuit breaker 20 which operates in a manner so well understood as to require no specific description. The circuit breaker contacts are shunted by a condenser 21. The 105 secondary winding 2 is grounded at one terminal and has its other terminal connected with the travelling contact member of a distributor 22 whose waiting contacts are connected with the spark plugs 23 in the 110

various cylinders of an internal combustion engine in a manner well understood. Other ignition circuits may be employed.

The winding element 1, 2 is disposed about a central magnetizable core portion of T shape having a stem 24 that is snugly received within the bore of the primary 1 and a head 25 that is disposed in an enlargement of the bore of the secondary 2. The straight side of the block 6 is held against one face of the T head 25 and the curved side of this block is snugly received within the insulating lining 26 upon the interior of the secondary 2, the block 6 and the contacts 5 and 7 thereon being thus held in fixed relation with the winding element within the bore thereof and in fixed relation with the core. A liner of insulation 27 adjacent the forward end of the primary 1 closes the hollow back of the block 6 to guard the screws 4 and 8 from improper connection.

The switch arm or lever 28 carries the insulating block 17 and extends across the outer face of the core head 25, this arm being then deflected inwardly, as indicated at 29, along the core head 25 which is thus disposed between this portion of the switch arm and a portion of the switching mechanism where the switch contacts are provided. Said switch arm 28 is radially extended, as indicated at 30, this radial extension having an oblong opening 31 which receives the oblong continuation 32 of a tumbler barrel 33. This tumbler barrel is mounted to turn in a shell or sleeve 34 which is slotted on its opposite sides, as indicated at 35, to receive the tumblers 36 when the key 18 is withdrawn. When the ignition circuit is to be closed, the key is inserted to withdraw the tumblers from the slots 35 whereafter the tumbler barrel is turned to close the primary circuit of the ignition system, as indicated in Fig. 8. When the tumbler barrel is turned, the tumblers are brought into line with the shell 34 so that the key can not then be withdrawn. When the ignition circuit is to be opened, the key is turned to bring the tumblers into register with said slots whereafter the key is withdrawn to permit the tumblers to enter the slots to lock the ignition circuit open. The portion 29 of the switch arm is of blunt V formation and is so located as to have one of its sloping faces or the other engageable with the core head 25 that serves to limit the throw of the switch arm to positively locate it in an ignition circuit opening or an ignition circuit closing position.

The winding element extends into the zone which contains the switching mechanism, the locking structure and the core head 25. Hitherto, the core or winding element, the switching mechanism and the locking structure have been in tandem, thereby consider-

ably increasing the overall length of the equipment. By arranging the locking mechanism and the switching mechanism abreast of each other and abreast of the core head 25 and surrounding them by the winding element, the overall length is not only reduced but the locking and switching mechanism are thoroughly protected from access of any tool passed to the same in their zone. The hollow in the winding element which receives the locking mechanism and switching mechanism is closed by an end wall 37 which with the winding element forms a casing that encloses the switch and lock. In the preferred embodiment of the invention the winding element is surrounded by a cylindrical sheath or shell 38 with which the end wall 37 is assembled by means of a cap plate 39 which is formed with the annular groove that receives the peripheral edge of the end wall 37 and the flange 40 on the shell 38. The locking shell or sleeve 34 is formed with a shoulder 41 which is received between the end wall 37 and the cap plate 39 and which is suitably secured to hold it in fixed relation to this wall and cap plate. The reduced outer end of a tumbler barrel 33 is passed through an opening in the cap plate 39. The end wall 37 and the cap plate 39 are slightly dished, as shown in Fig. 1, the dished portions of these elements being received in an opening in the mounting plate 42 to which the outfit is secured by means of the bolts 43.

Changes may be made without departing from the invention.

Having thus described my invention, I claim:

1. The combination with a current conducting winding element; of a circuit controlling switch in electrical association with said winding element; and a locking structure in controlling relation to the switch, said locking structure and switch being located abreast and within said winding element.

2. The combination with a current conducting winding element having a magnetizable core; of a circuit controlling switch in electrical association with said winding element; and a locking structure in controlling relation to the switch, said locking structure and switch being located within the winding element and on opposite sides of said core.

3. The combination with a current conducting winding element having a magnetizable core; of a circuit controlling switch in electrical association with said winding element; and a locking structure in controlling relation to the switch, said locking structure and switch being located within the winding element and abreast of said core.

4. The combination with a current conducting winding element having a magnetizable core; of a circuit controlling switch in electrical association with said winding ele-

ment; and a locking structure in controlling relation to the switch, said locking structure being located within the winding element and abreast of said core.

5. The combination with a current conducting winding element having a magnetizable core; of a circuit controlling switch in electrical association with said winding element; and a locking structure in controlling relation to the switch, said locking structure and switch being located on opposite sides of said core.

6. The combination with a current conducting winding element having a magnetizable core; of a circuit controlling switch in electrical association with said winding element; and a locking structure in controlling relation to the switch, said locking structure and switch being located within the winding element and on opposite sides of said core, said switch including a contact arm extending across the adjacent end of the core and coupled with the locking structure to be operable thereby.

25. 7. The combination with a current conducting winding element having a magnetizable core; of a circuit controlling switch in electrical association with said winding element; and a locking structure in controlling relation to the switch, said locking structure and switch being located within the winding element and abreast of said core, said switch including a contact arm extending across the adjacent end of the core

30. 35 and coupled with the locking structure to be operable thereby.

8. The combination with a current conducting winding element having a magnetizable core; of a circuit controlling switch in

40. electrical association with said winding element; and a locking structure in controlling

relation to the switch, said locking structure being located within the winding element and abreast of said core, said switch including a contact arm extending across the adjacent end of the core and coupled with the locking structure to be operable thereby. 45

9. The combination with a current conducting winding element having a magnetizable core; of a circuit controlling switch in electrical association with said winding element; and a locking structure in controlling relation to the switch, said locking structure and switch being located on opposite sides of said core, said switch including a contact 50 arm extending across the adjacent end of the core and coupled with the locking structure to be operable thereby.

10. The combination with a current conducting winding element having a magnetizable core; of a circuit controlling switch in electrical association with said winding element; and a locking structure in controlling relation to the switch, said locking structure and switch being located abreast of said core, 55 said switch including a contact arm extending across the adjacent end of the core and coupled with the locking structure to be operable thereby.

11. The combination with a current conducting winding element having a magnetizable core; of a circuit controlling switch in electrical association with and located within said winding element; and a locking structure in controlling relation to the switch, 70 said locking structure being located within the winding element and abreast of said core. 75

In witness whereof, I hereunto subscribe my name.

GEORGE L. CRAGG.
